SEESAW APPARATUS

John K. Milton and Curley Young, Chicago, Ill.;
said Young assignor to said Milton

Application September 1, 1937, Serial No. 162,022

5 Claims. (Cl. 272—54)

Our invention relates to see-saw apparatus, and more particularly to the type in which the see-saw is also rotatable in the nature of a merry-go-round, and our main object is to improve the construction of a device of this kind in a manner to make the same more practical, durable and attractive.

A further object of the invention is to construct the novel apparatus along lines of simplicity and easy assembly.

A still further object of the invention is to employ in the novel apparatus only such units as are strictly essential to the proper construction and operation of the apparatus, whereby to make the same inexpensive to produce.

An additional object of the invention is to employ parts in the novel apparatus which lend themselves most advantageously to impart safety and beauty to the apparatus.

20 A significant object of the invention is to include in the novel see-saw apparatus a simple brake unit to enable the same to be easily brought to a stop.

With the above objects in view, and any others which may suggest themselves from the description to follow, a better understanding of the invention may be had by reference to the accompanying drawing in which—

Figure 1 is a prospective view of the novel see-saw apparatus.

Fig. 2 is an enlarged duplication of the central portion of Fig. 1.

Fig. 3 is an elevation of such central portion, partly broken away; and

35 Fig. 4 is a section on the line 4—4 of Fig. 3.

Considering the development of the see-saw in the line of amusement apparatus, we are aware of the fact that see-saws have been devised which are capable of rotary travel as well as oscillatory motion. Usually, the structures involve a universal or other type of flexible joint in the center of the apparatus. While the developments which have so far come to our attention may be more or less sound in principle, we have not found any sufficiently practical or popular to be in use to any extent, and it has therefore been our purpose to develop a structure of this kind in ways consistent with modern requirements in respect to practicability, simplicity, appearance and safety.

In accordance with the foregoing, specific reference to the drawing indicates the novel see-saw apparatus in the general form of a post 10 and a pair of beams 11. The post is for the purpose of our invention made of light but sturdy

pipe, and the upper end of the same is enlarged with a part-spherical headpiece 10a.

The beams 11 do not meet the post directly, but enter a pair of elongated sockets 12 which are extended in diametrically opposite directions from a part-spherical cup 13. The cup is of a nature to receive the headpiece 10a of the post 10 and form part of a ball-joint therewith. The balance of the joint is formed by a part-spherical cap 14 which is extended with a circular flange 14a at its base. Here the flange meets a similar flange 13a extended from the cup 13, both flanges being perforated at 15 for a series of bolts 16 to secure them together, completing the ball joint.

As the apparatus is set up by sliding the beams 15 into the sockets 12, the latter are equipped with set screws 17 to secure the beams in place. While the beams and sockets may be of any cross-sectional form it is preferable that they be of the triangular sections indicated in Fig. 4, in order that their relative rotation may not be possible. This design presents a flat top and modernistic appearance, and we have found the material of the beams readily available in tubular stock.

The ends of the beams 11 are equipped with suitable seats 18, these being either plain or sprung in the manner of bicycle saddles for greater comfort. The seats are preferably built up in front as indicated at 18a to receive cross-handles 19 and so provide a good hold for each occupant.

The post 10 is adapted to receive a tubular extension 20 of a suitable length to place the see-saw at the proper height over the floor or ground. The extension is secured by a set screw 20a applied from the side of the post 10; and it may terminate in the butt form indicated at 20b if the apparatus is set on a floor, or with a spiked extension 20c in case it is fixed in the ground. In either case, the extension receives a base plate 21 to add to its stability upon the floor or ground, the base plate having a high neck portion 21a for the application of an upper set screw 21b at one side and a lower one 21c on the opposite side to rigidly secure the base plate to the post.

In order that the see-saw may be quickly brought to a stop from its oscillatory or rotary motion, we have provided a simple brake device originating with a handy lever 22 carried by one of the beams 11. As seen in Fig. 3, this lever takes the form of a rod 22a on the inside of the beam, such rod extending slidably into a bearing 13b formed in the cup 13. The bearing is

25

35

40

45

50

55

widened horizontally to accommodate a shoe 13c formed on the corresponding end of the rod 22a, a spring 23 from the beam serving to draw the rod inwardly, so that the shoe 13c bears on the 5 surface of the headpiece 10a. The lever 22 is operable in a longitudinal slot 22b whose outer end is of the bayonet type and serves to hold the lever in the retracted position. This is the normal position of the brake device when the see-saw is in use, but when it is desired to bring the 10 same to a stop, the lever 22 is simply released from the bayonet hold, in which event the pull of the spring 23 causes the brake shoe 13 to bear on the headpiece 10a with sufficient friction to 15 gradually bring the see-saw to a stop.

It will be evident from the above description that we have provided a see-saw apparatus which is not only attractive and neat in appearance, but is also efficiently constructed. The apparatus is mostly of tubular metal, so as to be both light and strong, making its cost and upkeep economical. Further, the ball joint is formed from a simple assembly which is easily taken apart in case any lubrication, repair or 20 other attention is required. Further, the ball joint cup is integrally extended with the sockets 12, whereby to make them amply strong to safely support the beams 11 either under the strains of weight or force. Further, the cap 14 forms a 25 smooth dome for the center of the apparatus, eliminating projecting or other mechanical parts which may either be a menace to safety or subject to tampering. Further, the novel apparatus may be adjusted to any suitable height by means 30 of the telescoping extension 20 in the post so as to render the same in proper position and safe to use. Further, the brake device is a handy control in case the occupants wish to have the see-saw slow down or stop, as this is otherwise difficult to do when the see-saw is in rotary or oscillatory action. Finally, the apparatus imparts 35

a modernistic ornamental effect due to the simplicity of its center post and peculiar formation of the extensions therefrom.

We claim:—

1. A see-saw apparatus comprising a center post formed with a headpiece of spherical curvature, a cup making a ball joint with the lower part of the headpiece, beams extended from opposite sides of the cup, and a cap supplementing the cup over the upper part of the headpiece. 10

2. The structure of claim 1, and means to secure the cap to the headpiece.

3. The structure of claim 1, the cup and headpiece being marginally flanged, the flanges having matching perforations, and a series of bolts 15 applied by way of the latter to secure the flanges together.

4. A see-saw apparatus comprising a center post formed at the top with one component of a ball joint, a member below forming the other 20 component thereof, extensions from said member in opposite directions, and seats at the outer ends of the extensions.

5. A see-saw apparatus comprising a center post having a headpiece with a spherical curvature, a cup forming a ball joint with the headpiece, extensions from opposite sides of the cup forming the see-saw beams, and a device carried by one of the extensions and effective as a 25 brake on said headpiece, the device including a 30 rod disposed longitudinally in the extension, a shoe on the inner end of the rod and effective when the rod is actuated in the inward direction, a spring drawing the rod in the brake-applying direction, the extension being tubular and with 35 a bayonet slot, and a lever continuation passing through the latter and operable to lock the brake in the released position upon the retraction of the lever.
